UNITED STATES PATENT OFFICE.

ARY KAUFMANN, OF NEWARK, NEW JERSEY, ASSIGNOR TO K. KAUFMANN & CO., A CORPORATION OF NEW JERSEY.

BAG-BODY WITH INTEGRAL CORNER-PIECES.

1,119,517.

Specification of Letters Patent.

Patented Dec. 1, 1914.

Application filed January 23, 1914. Serial No. 813,836.

To all whom it may concern:

Be it known that I, ARY KAUFMANN, a citizen of the United States, residing at Newark, in the county of Essex and State of New Jersey, have invented certain new and useful Improvements in Bag-Bodies with Integral Corner-Pieces; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in traveling bags, suit-cases, and the like, provided at their respective corners with corner-pieces, and, the present invention has reference, more particularly, in providing the leather bodies of bags, suit-cases, and the like, at their respective corners with corner-pieces which are forced up directly out of the leather body, so as to provide a corner-piece which is integrally united with and forms a direct part of the leather body.

The present invention has for its principal objects to provide a novel and simple leather body for bags, suit-cases, and the like, formed with corner-pieces pressed out of the leather and integrally united with the leather-body, with a view of economizing in the leather, because the extra corner-pieces heretofore used are entirely done away with, and also greatly reducing the cost of the construction of the bag because the necessary stitching as well as the riveting in place of extra corner-pieces, as heretofore, is also obviated.

The invention has for its further object to provide the leather body of a bag, suit-case, or the like, with reinforcing corner-pieces, and also, if desired, with reinforcing edge-members, forming an integral part or parts of the body, with a view of greatly enhancing the general appearance and beauty of the body of the bag, suit-case, or the like, because there are no raw edges to the corner-pieces or to the reinforcing edge-members, and which edges can not turn up to provide unsightly edges, as with the constructions of the separately attached corner-pieces, or the separately attached reinforcing edge-mem-

bers. Furthermore, with the forms of separately attached corner-pieces and the separately attached reinforcing edge-members, the stitching employed for securing these elements in position upon the body of the bags, suit-cases, or the like, are placed upon the tops of the said elements, which causes the corner-pieces or reinforcing edge-members to wear easily from rubbing, etc., and hence also easily wearing out the stitching, so that the corner-pieces or the reinforcing edge-members will readily come loose or wear off; and, another object of the present invention, therefore, is to arrange the stitching about the corner-pieces or the reinforcing edge-members in such a manner, that the stitching is not exposed to any wear, and being protected against wearing off, there will be no rubbing or coming off of the corner-pieces or of the reinforcing edge-pieces.

Other objects of this invention not at this time more particularly enumerated will be clearly understood from the following detailed description of the present invention.

With these various objects of the present invention in view, the present invention consists, primarily, in the novel combined body and corner-pieces, or the combined reinforcing edge-members therefor, of bags, suit-cases, and the like; and, the invention consists, furthermore, in the novel arrangements and combinations of the several devices and parts, all of which will be more fully described in the following specification, and then finally embodied in the clauses of the claim which are appended to and which form an essential part of the said specification.

The invention is clearly illustrated in the accompanying drawings, but while in the said drawings I have illustrated my present invention as applied to the body of a traveling bag, the fact must not be lost sight of that the invention is also applicable to the bodies of all styles and kinds of bags, as well as to suit-cases, and the like.

In the said drawings, Figure 1 represents one style of bag, the bag-body of which is provided with integrally formed corner-pieces, showing one embodiment of the principles of the present invention. Fig. 2 is a fragmentary face-view of a portion of a bag-body provided with a reinforcing edge-member forming an integral part of the said

body, said member being in the shape of a corner-piece, and said view illustrating in connection therewith portions of the backing usually employed with the body; and Fig. 3 is a horizontal sectional representation of the parts illustrated in said Fig. 2, said section being taken on line 3—3 in said Fig. 2. Fig. 4 is a bottom view of the bag represented in said Fig. 1. Fig. 5 is a perspective view of a bag, the bag-body of which is provided with reinforcing edge-members forming integral portions of the said bag-body, and made in the form of combined corner-pieces and edge-members extending along the gusset-ends and the sides of the bag-body; and Fig. 6 is a fragmentary perspective view of a bag-body provided with reinforcing edge-members forming integral portions of said bag-body, and made in the form of combined corner-pieces and edge-members extending along the gusset-ends of the bag-body. Fig. 7 is a perspective view of another form of bag provided with corner-pieces made according to and embodying the principles of the present invention; and Fig. 8 is a fragmentary face-view of a portion of one of the gusset-ends of the bag-body, combined with a corner-piece forming an integral part of said gusset-end.

Similar characters of reference are employed in the said above described views, to indicate corresponding parts.

Referring now to Figs. 1, 2, 3, 5 and 6 of the drawings, the reference-character 1 indicates the bag-body of a traveling bag, which is made of leather, and in the styles of bags represented in said figures of the drawings is usually made in two pieces which are stitched together, as at 2, at the gusset-ends of the bag, and as is illustrated in Fig. 4 of the drawings, are turned inwardly at their lower marginal edge-portions, as at 3, and are suitably secured in any manner to a bottom 4.

In the bag shown in Figs. 1, 2 and 3 of the drawings, the leather which forms the body of the bag, has outwardly pressed therefrom in those portions which are to provide the corners of the bag-body, suitably shaped reinforcing edge-portions, as 5, integrally united with the main parts of the bag-body and the marginal raised portions 7 of said parts 5 being rounded, as shown more particularly in Fig. 3 of the drawings, so as to avoid raw edge portions, and made in the conventional configuration of the usual corner-pieces, now made separately from the bag-body, and secured thereto by 60 rows of stitching on top of the corner-piece, and sometimes additionally secured in position by means of rivets.

In the present construction, stitching, as at 6, may be provided, such stitching instead of being on the top of the raised edge-ports

tions 5 and at the marginal edge-portions 7 thereof, is provided directly at the lower surface-portions of the bag-body, adjacent to the raised edge-portions 7 of the said pressed-out reinforcing edge-portions or 70 members 5 formed integrally with the bag-body.

The reference-character 8 indicates the usual backing, of card-board or other suitable material, secured upon the back of the bag-body by means of said stitching, and in the pocket 9 formed between the said backing and the raised edge-portions 5 pressed out of said bag-body is a filler 10 of any suitable material, which reinforces and strengthens the corners of the bag-body, and helps the said raised edge-portions to retain their shapes of corner-pieces, by preventing the collapsing of said raised edge-portions 5, as will be clearly evident. The 85 said filler 10, it will be understood, may be made of card-board, sheet metal, fiber, and in fact any other suitable material may be used which will greatly strengthen the body of the bag at the points where said raised edge-portions are provided.

In the style of bag represented in Fig. 5 of the drawings, the leather bag-body 1 is also made in two pieces which are sewed or stitched together, as at 2, at the gusset-ends 95 of the bag. The leather which forms the body of the bag, in this instance, has outwardly pressed therefrom in those portions which are to provide the corners of the bag-body, as well as along the marginal edges 100 of the side-faces and the gusset-ends suitably-shaped reinforcing edge-members or portions, as 11—12—13, the corner-portions 12 being of such conformation to produce the general appearance of corner-pieces, as 105 will be seen from an inspection of said Fig. 5 of the drawings. The said edge-members or portions 11—12—13, being forced out of the main body-portion of the bag, are integrally united therewith. Stitching, as 14, 110 may also be provided, such stitching extending directly along the lower surface-portions of the bag-body, adjacent to the raised edge-portions 15 of the said pressed-out reinforcing edge-members 11—12—13 which form 115 an integral part of the bag-body. In lieu of the general configuration of the raised reinforcing edge-members 11—12—13, as shown in said Fig. 5, or, instead of the corner-piece edge-members 5, represented in 120 Figs. 1 and 2 of the drawings, the bag-body may be provided with raised and integral reinforcing edge-members 16—17, as illustrated in Fig. 6 of the drawings, the parts 16 forming raised portions of the general 125 corner-piece conformation, and the raised parts 17 extending along the marginal edge-portions of the gusset-ends of the bag-body. Of course, it will be understood, that in connection with the styles of bag-bodies repre- 130

sented in said Figs. 5 and 6, is employed the backing 8 and correspondingly shaped fillers 10 mentioned in connection with the construction of bag-body illustrated in Figs. 1, 5 2 and 3 of the drawings. Stitching, as 18, may be arranged closely to the marginal edge-portions 19 of the raised parts 16-17, as shown in said Fig. 6.

Referring now to Figs. 7 and 8 of the 10 drawings, in which is represented a style of bag, the leather body of which has its side-pieces 20 sewed to the gusset ends 21, at their edges 22. In this construction of bag-body, as will be seen more particularly from 15 an inspection of Fig. 8, the gusset-ends 21 are formed at their respective corners 23, with the pressed out edge-portions 24, these portions 24 being made with parts 25 which extend beyond the marginal edges 26 of the 20 gusset-ends, the pressed-out portions 24 and the marginally extending parts 25 being made so as to conform to the general configurations of the usual corner-pieces, as will be clearly seen from an inspection of said 25 Figs. 7 and 8 of the drawings. In stitching the side-pieces 20 and gusset-ends 21 along the edges 22, the projecting parts 25 are lapped over the corner-portions 28 of the side-pieces 20, and then sewed fast by means 30 of the stitching 29, all of which will be clearly understood from an inspection of said Fig. 8.

While in the above, I have described my present invention as applied to the leather 35 bodies of traveling bags, it must be clearly understood that the invention is also applicable to other shaped bodies, as to the bodies of suit-cases, and the like, and the invention may also be applied to that class 40 of bags known in the trade as ladies' shopping or hand-bags. It will also be understood, that the various raised edge-members may also, if desired, be provided directly upon their raised parts with stitchings 29, 45 in the manner indicated in Fig. 2 of the drawings. I am aware, also, that changes may be made in the general arrangement of the integrally formed raised marginal edge-members with relation to the main portions 50 of the bag-body, as well as in the general marginal conformations of the said raised edge-members, whether in the shapes of corner-pieces or otherwise, without departing from the scope of the present invention as 55 described in the foregoing specification and as defined in the clauses of the claim which are appended thereto. Hence, I do not limit my invention to the exact arrangements and combinations of the various parts, nor to the exact marginal configurations of the 60 raised and pressed-out parts forming integral parts of the main body of the bag, suit-case, or the like.

I claim:—

1. A leather bag or case, having a lining

and non-separable corners, reinforcements consisting of fillers inserted between the outside leather and the lining and confined in place by stitches made around them through the leather and lining. 70

2. A leather bag or case, having a lining and corner pockets formed between the outer leather and the lining and fillers in said pockets serving as reinforcing means and confined in place by stitches made 75 around the same through the outer leather and the lining.

3. As an article of manufacture, a body for bags, suit-cases, and the like, said body having pressed-out raised edge-members, 80 said members forming integral parts of said body, and the marginal raised edge-portions of said pressed-out parts being substantially rounded so as to avoid raw edge-portions, combined with a backing, and a filler between said backing and the pressed-out 85 raised edge-members.

4. As an article of manufacture, a body for bags, suit-cases, and the like, said body having pressed-out raised edge-members, 90 said members forming integral parts of said body, and the marginal raised edge-portions of said pressed-out parts being substantially rounded so as to avoid raw edge-portions, and stitching in the main body contiguous 95 to the raised marginal edges of the edge-members.

5. As an article of manufacture, a body for bags, suit-cases, and the like, said body having pressed-out raised edge-members, 100 said members forming integral parts of said body, and the marginal raised edge-portions of said pressed-out parts being substantially rounded so as to avoid raw edge-portions, combined with a backing, and a filler between 105 said backing and the pressed-out raised edge-members, and stitching in the main body contiguous to the raised marginal edges of the edge-members.

6. As an article of manufacture, a body 110 for bags, suit-cases, and the like, said body having pressed-out raised corner-pieces, said corner-pieces forming integral parts of said body, and the marginal raised edge-portions of said pressed-out corner-pieces being substantially rounded so as to avoid raw edge-portions, combined with a backing, and a filler between said backing and the pressed-out corner pieces. 115

7. As an article of manufacture, a body 120 for bags, suit-cases, and the like, said body having pressed-out raised corner-pieces, said corner-pieces forming integral parts of said body, and the marginal raised edge-portions of said pressed-out corner-pieces being substantially rounded so as to avoid raw edge-portions, and stitching in the main body contiguous 125 to the raised marginal edges of the corner-pieces.

8. As an article of manufacture, a body 130

for bags, suit-cases, and the like, said body having an integral pressed-out raised member, combined with a backing, and a filler between said backing and the integral pressed-out raised member.

9. As an article of manufacture, a body for bags, suit-cases, and the like, said body having pressed-out raised corner-pieces, combined with a backing, and a filler between

said backing and pressed-out raised corner-¹⁰ pieces.

In testimony that I claim the invention set forth above I have hereunto set my hand this 21st day of January, 1914.

ARY KAUFMANN.
